UNITED STATES PATENT OFFICE.

GERTRUDE I. LANDRY, OF PAWTUCKET, AND GEORGE S. KELLEY, OF PROVIDENCE,
RHODE ISLAND.

HAIR-RETAINING DEVICE.

1,306,068.

Specification of Letters Patent. Patented June 10, 1919.

Application filed February 8, 1919. Serial No. 275,732.

To all whom it may concern:

Be it known that we, GERTRUDE I. LANDRY and GEORGE S. KELLEY, citizens of the United States, and residents of Pawtucket and Providence, respectively, in the county of Providence and State of Rhode Island, have invented certain new and useful Improvements in Hair-Retaining Devices, of which the following is a specification.

10 This invention relates to a hair-retaining device more particularly adapted for curling or crimping the hair, and has for its object to provide such a hair holder or crimper which may also be used as a barrette when 15 desired, the same being constructed of a narrow strip of resilient material of convenient length folded upon itself so that its two opposing arms are adapted to grip, press and crimp the hair between them 20 which is wound spirally around one of the arms, a removable guard being provided for locking the ends of said arms together.

With these and other objects in view, the invention consists of certain novel features 25 of construction, as will be more fully described, and particularly pointed out in the appended claim.

In the accompanying drawings:

Figure 1— is a top view of our improved 30 hair retainer, showing the end guard in dotted lines swung off to one side.

Fig. 2— is an edge view showing the two arms of the retainer in their normal position when released.

35 Fig. 3— illustrates the two arms as folded together by hand pressure of the user with the guard ready to be swung back into position to lock the ends together.

Fig. 4— is a perspective view showing the 40 arms as locked together by the swinging guard.

Fig. 5— is an enlarged section on line 45 5—5 of Fig. 4, showing the recess in the guard and the corresponding rib on the arm for locking the guard in engaging position.

With reference to the drawings, our improved hair retaining device is constructed 50 of a convenient length, preferably of a thin strip of spring stock folded upon itself at its middle portion forming an open loop 10 with two resilient normally separated opposing arms 11 and 12. At the extremity 13 of arm 12 is pivotally mounted at 14 a guard member 15 bent into the form of a hood or hook, the nose 16 of which being

struck up or recessed as at 17 for the purpose of receiving a corresponding rib or raised portion 18 formed on the opposite arm 11 to snap into and releasably retain the guard member in engagement therewith by tension of the inherent spring in the arms.

In operating our improved hair-retaining device it is only necessary to wind the hair about the arm 11, then press arms 11 and 12 together by the thumb and finger and swing the guard member 15 around in line with the axis of these arms so that the recess 17 in the nose portion 16 of the guard is engaged by the rib 18 in the opposite arm to securely yet readily releasably retain these arms in closed position against any strain which may be applied thereto.

When it is desired to release these arms it is only necessary to rotate the guard 15 laterally or off to one side or out of line with the axis of these arms by which action both arms are released to spring to open or normal position, and when the arms are to be secured in closed or operative position their 80 ends are pressed together and the hook or hood member is swung back into alignment therewith and the free end of the hook or hood portion is caused to engage the end of the free arm to inclose and protect the same 85 and firmly hold the two arms together.

In addition to serving as a hair crimper it may be suitably ornamented and also serve as a barrette if desired.

We do not wish to be restricted to the 90 hinging or pivoting of the locking member upon one of the arms as any means by which this locking member may be mounted on one arm to be moved relatively thereto into position to engage, cover and protect the other 95 arm and lock them both together and out of position to release the same, will fall within the spirit and scope of this invention.

We do not wish to be restricted to the use of our improved device for curling hair 100 as the same may be used for any purpose for which it is adapted.

The device is extremely simple in construction and very effective in its operation and may be most readily locked and unlocked as the guard which is of a loop construction serves as a most convenient handle by which it may be operated.

The foregoing description is directed solely toward the construction illustrated, 110

but we desire it to be understood that we reserve the privilege of resorting to all the mechanical changes to which the device is susceptible, the invention being defined and limited only by the terms of the appended claim.

We claim:

A hair retainer comprising a relatively broad strip of resilient material folded upon itself forming two opposing arms adapted to engage each other with spring pressure,

said arms being relatively unyielding laterally, and a hood-shaped guard member pivoted to one arm adjacent its end and adapted to be swung over the end of the other 15 arm to engage, inclose and protect this end and to lock both arms together against springing apart.

In testimony whereof we affix our signatures.

GERTRUDE I. LANDRY.
GEORGE S. KELLEY.
